UNITED STATES PATENT OFFICE.

AMOS N. HAMLET, OF ELK POINT, SOUTH DAKOTA.

FILTER.

1,164,508.

Specification of Letters Patent.

Patented Dec. 14, 1915.

Application filed April 26, 1915. Serial No. 23,967.

To all whom it may concern:

Be it known that I, AMOS N. HAMLET, a citizen of the United States, residing at Elk Point, in the county of Union and State of South Dakota, have invented certain new and useful Improvements in Filters; and I do hereby declare the following to be a full, clear, and exact description of the invention, such as will enable others skilled in the art 10 to which it appertains to make and use the same.

This invention relates to improvements in filters.

The object of the present invention is to 15 improve the construction of rain water filters and to provide a simple, practical, and comparatively inexpensive filter of this character adapted to be readily applied to either side of a house and to be reversed to accommodate a rain spout at either end of it without necessitating any alteration in its construction.

A further object of the invention is to provide a rain water filter adapted to afford 25 ready access to its interior and capable of being easily cleaned.

With these and other objects in view the invention consists in the construction and novel combination and arrangement of parts 30 hereinafter fully described, illustrated in the accompanying drawings and pointed out in the claims hereto appended, it being understood that various changes in the form, proportion and minor details of construction 35 may be resorted to without departing from the spirit or sacrificing any of the advantages of the invention.

In the drawings Figure 1 is a vertical sectional view of a rain water filter constructed 40 in accordance with this invention, Fig. 2 is a transverse sectional view on the line 2--2 of Fig. 1, Figs. 3 and 4 are detail sectional views illustrating the construction of the inlet openings and the removable slidable clo- 45 sure therefor.

Like numerals of reference designate corresponding parts in all the figures of the drawings.

In the accompanying drawings in which 50 is illustrated the preferred embodiment of the invention 1 designates an outer casing designed to be constructed of galvanized sheet metal or other suitable material and

comprising a horizontal bottom, side and end walls and a removable lid or cover 2 having 55 downwardly bent or curved engaging edges 3 which slidably interlock with beads 4 located at opposite ends of the outer casing as clearly illustrated in Fig. 1 of the drawings. The outer casing which is of rectangular 60 form is provided at the end portions of its removable lid or cover with inlet openings 5 and 6 having inclined flanges 7 extending upwardly and outwardly and adapted to receive a slidable closure 8 which may be 65 arranged on the flanges of either of the inlet openings 5 and 6 to enable a rain spout 9 to be connected with either end of the casing. By this construction the filter may be located at either side of a building and connected at 70 either end with the rain spout and one inlet opening is uncovered to receive the rain spout 9 and the other is closed by the slidable cover or closure 8.

Within the outer casing is arranged an 75 inner reversible casing 10 composed of imperforate side walls 11, an imperforate bottom 12, an end wall 13 and foraminous transverse partitions 14 and 15. The inner 80 reversible casing which may be constructed of galvanized sheet metal or any other suitable material is arranged upon the bottom of the outer casing with its bottom 12 supported above the bottom of the outer casing by lower extensions 16 of the side walls of 85 the inner reversible casing. The sides of the reversible casing are also provided at one end of the said inner casing with extensions 17 located at the upper portions of the side walls and the end wall 13 is composed of 90 upper and lower vertical portions 18 and 19 and inclined connecting portions 20, suitably connected with the side walls at the said extension 17 thereof. This construction pro- 95 vides an upper extension at one end of the casing and a recess 21 below the extension which is of a length to extend beneath and slightly beyond the lower end of the rain spout 5 so that all of the water passing downward through the same will enter the 100 inlet chamber or compartment 22 between the front wall 13 and the inner foraminous partition 14. The partitions 14 and 15 are preferably constructed of woven wire and the space between the same forms a filter 105 compartment adapted to receive filtering

material 23 such as charcoal or the like. The water entering the inlet chamber or compartment passes through the filtering material and leaves the inner casing at the 5 transverse partition or wall 15.

The outer casing is provided at the bottom at one end with a short pipe or nipple section 24 piercing the bottom and extending upwardly and downwardly therefrom. The 10 upwardly extending portion 25 receives a screen 26 of closely woven wire. The screen which is of cylindrical form is open at the bottom to fit over the projecting upper portion 25 of the nipple 24 and the depending 15 portion 27 of the nipple is threaded for the reception of a threaded portion 28 of a cistern pipe 29.

The slideable lid or cover is readily removable to afford access to the interior of the 20 outer casing and the inner casing is adapted to be readily removed and reversed to arrange its extension end portion and the water inlet compartment or chamber beneath the rain spout which may be located at either 25 of the openings 5 and 6. It will be seen that this construction will save time and labor in applying the filter to a building and that it may be located at either side of a building and may have the rain spout connected with either end of it without altering 30 its construction. The outer casing is also provided at the bottom with a flanged drain opening 30 normally covered by a screw cap 31 which is adapted to be removed for clean-

ing out the outer casing of any sediment 35 which may collect therein.

What is claimed is:—

1. A filter of the class described including an outer casing provided at the top with spaced inlet openings adapted to receive a 40 rain spout to permit the rain spout to be connected with opposite portions of the casing, the latter being provided at the bottom with an outlet, and a reversible inner casing provided with a filter compartment and having 45 a water inlet compartment or chamber arranged to extend beneath either one of the inlet openings.

2. A filter of the class described including an outer casing provided at the top with spaced inlet openings adapted to receive a 50 rain spout to permit the rain spout to be connected with opposite portions of the casing, the latter being provided at the bottom with an outlet, a reversible inner casing provided with a filter compartment and having 55 a water inlet compartment or chamber arranged to extend beneath either one of the inlet openings, and a removable closure 60 adapted to be arranged on either of the inlet openings to cover the one not in use.

In testimony whereof I affix my signature in presence of two witnesses.

AMOS N. HAMLET.
